(57) **CLAIM**

The ornamental design for a lamp, substantially as shown and described.

DESCRIPTION

FIG. 1 is a front perspective view of a lamp, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a usage state perspective view;

FIG. 10 is an enlarged view of the portion labeled “10” in FIG. 1; and,

FIG. 11 is an enlarged view of the portion labeled “11” in FIG. 1.

The long-dash short-dash broken lines surrounding portions of the lamp in FIGS. 1, 10, and 11 form no part of the claimed design.
